DESIGN FOR A CASING FOR FLEXIBLE MEASURING RULES

**Austin L. Stowell, New Britain, Conn., assignor to
The Stanley Works, New Britain, Conn., a cor-
poration of Connecticut**

Application June 14, 1935, Serial No. 57,269

Term of patent 14 years

To all whom it may concern:

Be it known that I, Austin L. Stowell, a citizen of the United States and resident of New Britain, in the county of Hartford, State of Connecticut, have invented a new, original, and ornamental Design for a Casing for Flexible Measuring Rules, of which the following is a specification, reference being had to the accompanying drawing, forming part thereof.

Figure 1 is perspective view of the casing showing my new design;

Fig. 2 is an edge view of the casing; and

Fig. 3 is a sectional view thereof taken through the center.

I claim:

The ornamental design for a casing for flexible measuring rules, as shown.

AUSTIN L. STOWELL.
